pany, Chicago, Ill., a corporation of Ohio

No Drawing. Application February 12, 1945,
Serial No. 577,582

14 Claims. (Cl. 260—666)

1

This invention relates to a method of separating ring-type hydrocarbons from open-chain or aliphatic hydrocarbons.

We have discovered that aqueous alkali solutions containing in solution naphthenic acid salts or partially oxidized petroleum hydrocarbons, have the ability to selectively dissolve aromatic hydrocarbons and other closed-ring hydrocarbons from admixtures with open-chain hydrocarbons. Tests made on a number of hydrocarbons with both open-chain and closed-ring structure show that the compounds of closed-ring structure are considerably more soluble in aqueous alkali solutions containing naphthenic acids and/or partially oxidized petroleum hydrocarbons than are the open-chain compounds, and by reason of the difference in solubility, hydrocarbon mixtures containing open-chain and closed-ring hydrocarbons can be separated into one or more fractions more concentrated in closed-ring hydrocarbons than is the original hydrocarbon mixture.

An object of the invention is to provide a method for separating open-chain hydrocarbons from closed-ring hydrocarbons.

Another object of the invention is to prepare from a mixture of open-chain and closed-ring hydrocarbons a fraction more concentrated in open-chain hydrocarbons.

A further object of the invention is to prepare from a mixture of open-chain and closed-ring hydrocarbons a fraction more concentrated in closed-ring hydrocarbons.

Other objects of the invention will become apparent from the following description.

The extracting solution which is used in accordance with our invention is made by dissolving in aqueous alkali solution, preferably either sodium or potassium hydroxide solution, naphthenic acids and/or aqueous alkali soluble oxidation products resulting from the partial oxidation of hydrocarbons or the alkali metal soaps there-

2

of. When naphthenic acids are used, a solventizer, that is, a substance which will cause the naphthenic acids or soaps to go in solution in the aqueous alkali, is also added.

5 As solventizers to keep the naphthenic acids in solution, may be used such compounds as ethylene glycol, phenols including phenol, o-, m- and p-ethyl phenol, normally liquid xylenols and mixtures thereof, cresols, 2,3,5-trimethyl - phenol, 10 butyl-pyrogallol, 3,4,-dihydroxydiphenyl, p-chlor-m-cresol, alpha-naphthol, thiophenols such as thiophenol, o- and m-thiocresol, chlorphenols such as o- and p-chlorphenol and 2,4,5-trichlorphenol. Alkyl phenols such as the various cresols and mixtures of cresols have been found to be particularly effective solventizers.

15 By the term "naphthenic acids" it is intended to include all alicyclic acids particularly those which occur naturally in crude petroleum and which are predominantly cyclic in structure such as carboxylic acids of cyclo-pentane and cyclo-hexane ring structure. These acids, generally speaking, fall within the empirical formulae $C_nH_{2n-1}COOH$, $C_nH_{2n-3}COOH$ and

20 $C_nH_{2n-5}COOH$

25 and contain a cyclo-paraffinic ring having a carboxyl group attached to carbon in the ring or to an aliphatic chain which is in turn attached to carbon in the ring. The acids may be mono or poly cyclic, usually the former. An increase in the length of the aliphatic chain or in the number of aliphatic group substituents increases the 30 tendency of the acids to behave as aliphatic acids. Since soaps of aliphatic acids, even those of as low molecular weight as heptylic acid, are too insoluble in sodium hydroxide solution to possess substantial merit as mercaptan solubility promoters, it is not desirable to have too many aliphatic carbon atoms per molecule present be-

cause of the concomitant low solubility. It is accordingly preferred to use those naphthenic acids which have at least a definite minimum solubility in aqueous alkali solution. Acids which have this alkali solubility are those acids which dissolve substantially completely to the extent of 18.7 pounds in a solution consisting of 18.3 pounds of sodium hydroxide, 6.3 pounds of commercial 5° cresol and 56.7 pounds of water at temperatures of about 70° F. It is apparent that in applying this solubility test to compositions containing mixtures of naphthenic acids of varying molecular weight and structure, that some of the acids may dissolve and others remain undissolved. If the dissolved acids are soluble to the aforementioned extent, they are alkali-soluble within the meaning of this invention. Naphthenic acids containing over about 8 or 9 carbon atoms per molecule, such as those containing between about 11 and 16 carbon atoms, are particularly effective.

The following Table I is characteristic of naphthenic acids which are suitable for use in preparing solutions for use in practising this invention.

¹ Cracking.

The acidic oxidation products of petroleum hydrocarbons which may be used in preparing the extracting solution may be formed by either the vapor or liquid phase, preferably the latter, partial oxidation of normally liquid or solid petroleum hydrocarbons. This oxidation may be carried out with air or oxygen or other oxidizing agents, with or without catalysts, at any desired superatmospheric pressure but is ordinarily not in excess of about 160° C., although higher temperatures may be employed.

The products produced by oxidation of petroleum oils ordinarily vary considerably in composition, although it is generally believed that a major portion of the oxidation products are acidic in character, probably of the nature of fatty acids. Crude oxidation mixtures, resulting from the liquid phase oxidation of paraffin wax, have been known to contain higher fatty acids, and their anhydrides, oxy-acids, alcohols, ketones, alcohol-ketones, lactones and unsaturated acids.

The petroleum acidic oxidation products may be obtained, for example, by blowing air through kerosene or melted paraffin wax in the presence of suitable catalysts such as potassium permanganate and other manganates and permanganates of the alkali metals or ammonium. One method of preparing such acidic material is to melt crude

scale wax derived from petroleum and mix therewith an aqueous solution containing a small amount of potassium permanganate and soda ash. This mixture is heated to a temperature of about 110° C. and air forced through the mixture for a period of about 18 hours. This reduces the unsaponifiable content of the mixture to about 65%. The oxidized acidic materials are obtained by neutralizing the oxidation mixture with aqueous alkali at a temperature of about 170° C., and a pressure of about 100 p. s. i. The resulting water solution of the alkali reaction products is separated from the water insoluble material and the aqueous solution extracted with naphtha to more completely remove unsaponified material. The aqueous solution is acidified with dilute sulphuric acid and the acidic oxidation products set free. These are dried and may be fractionated by distillation under vacuum. A distillation may, if desired, be carried out on the crude oxidation mixture prior to saponification.

The acidic products derived by oxidation of petroleum hydrocarbons differ as to odor and appearance from similar pure straight chain fatty acids of approximately the same molecular weight. They also differ in that they do not readily solidify at low temperatures. Analysis of the crude mixtures obtained as a result of the oxidation process is particularly difficult because of the lack of stability of some of the oxidation products which products break down upon distillation, thus producing new materials not originally present in the crude oxidation mixture.

The acidic oxidation mixture, whatever its exact composition may be, is soluble in aqueous alkali solutions and materially enhances the ability of such solutions to dissolve liquid hydrocarbons. While oxidation mixtures from any of the less volatile petroleum hydrocarbons are useful in accordance with this invention, it is preferred to use those oxidation products obtained by the oxidation of relatively high molecular weight petroleum hydrocarbons, such as those hydrocarbons of about 10 to 30 carbon atoms.

A petroleum oxidation product which we have found particularly effective, hereinafter referred to as Product A, is prepared by catalytic air oxidation of 36 to 40 Baumé gravity Pennsylvania petroleum distillate and has the following properties:

Table II

Bé. gravity at 158° F.	11-9°
Specific gravity at 158° F.	1.007-0.9930
Viscosity (Saybolt) at 210° F.	91-101
Cold test (A. S. T. M.)	20-25° F.
Flash (C. O. C.)	250-270° F.
Fire (C. O. C.)	280-300° F.
Acid number	110-130
Saponification number	190-210
Iodine number	20 maximum
Ash	0.5-1.0

In order to demonstrate the difference in solubility of open-chain and ring hydrocarbons in alkali solutions containing naphthenic acids or oxidized petroleum hydrocarbons, a series of tests was made in which different hydrocarbons were dissolved into different solutions and the amount of solution of the hydrocarbon in the extraction solvent determined. Two methods were used to determine the extent of solution of hydrocarbons in the aqueous alkali solution: (1) the vapor pres-

sure method, and (2) the settling method. In the vapor pressure method, small amounts of hydrocarbons were added to the alkali solution in an extraction burette and the mixture was shaken, after which the vapor pressure above the solution was determined. This procedure was continued until further addition of hydrocarbon had no effect on the vapor pressure. As larger amounts of hydrocarbons are dissolved in the alkali solution, the partial pressure of the hydrocarbon increases until the solution has become saturated with hydrocarbons. Further addition of hydrocarbon produces no further effect on the vapor pressure. All measurements were taken after the burette had been placed in a water bath maintained at constant temperature and the burette allowed to remain therein for a sufficient period of time so that the pressure became constant.

In the settling method, the extraction solution was mixed with an excess of hydrocarbon and allowed to stand at the temperature selected for solution. After several days standing, a sample of the caustic solution was withdrawn and the hydrocarbon content was determined by means of the A. S. T. M. apparatus for determining the dilution of crank-case oils. In every case where the settling method was used, the mixture of hydrocarbon and aqueous alkali solution was allowed to stand in a constant temperature water bath until the concentration of hydrocarbon in the caustic solution became constant.

The naphthenic acid-containing solution is designated as Solution M and the Product A containing solution is designated as Solution A.

Table III

Composition of Extracting Solution, Per Cent by Wt.	Hydrocarbon	cc. of Hydrocarbon dissolved per 100 cc. of Extracting Solution at 100° C.		40

It is apparent from the table that cyclic hydrocarbons are more soluble in the alkali solution than are the open-chain hydrocarbons and that this difference in solubility is even more marked in the case of the alkali solution containing Product A than in the case of the solution containing naphthenic acids. Tests were made us-

ing a plain 20% sodium hydroxide solution and the solubility of the hydrocarbons in this solution was substantially nil. Alkali solutions containing other known solubility promoters, such as isobutyric acid, and high boiling tar acids were tried but these materials had very little solubility effect on the hydrocarbons.

In Table IV is given solubility at various temperatures of various open-chain and closed-ring hydrocarbons in Solution M.

Table IV

[Solubility measured as cc. of hydrocarbon per 100 cc. of solvent of various hydrocarbons at different temperatures prepared by mixing 18.3 parts by weight of NaOH, 18.7 parts by weight of naphthenic acids, 6.3 parts by weight of commercial cresols and 56.7 parts by weight of H₂O (Solution M).]

35 This table, like the preceding table, shows the difference in solubility in the alkali solution between open-chain and closed-ring hydrocarbons. The difference in solubility is particularly marked with respect to cyclohexene.

40 In order to demonstrate the ability of alkali solutions containing naphthenic acids and oxidized petroleum hydrocarbons to separate ring hydrocarbons from open-chain hydrocarbons, a blend of 30% by volume of toluene and 70% by volume of normal heptane was prepared and the blend was subjected to extraction with Solution M. 800 cc. of Solution M was contacted with 140 cc. of hydrocarbon mixture and the mixture was then permitted to settle and separate into two layers. The layers were separated and the hydrocarbon was recovered by distillation from the lower layer. 59 cc. of distillate was recovered from the lower layer and this was again extracted with 300 cc. of Solution M and the hydrocarbon recovered by distillation from the lower layer as before, amounted to 24 cc. 24 cc. of hydrocarbon was again contacted with 125 cc. of Solution M and 10 cc. of hydrocarbon was recovered from the lower layer. In the following 45 60 Table V is given the data with respect to the quantity, refractive index and toluene content of the several extracts and raffinates produced in the extraction.

Table V

	cc. Solution M Used	cc. of Hydrocarbon Treated	Hydrocarbons Recovered from Extract Layer			Hydrocarbons Remaining in Upper or Raffinate Layer		
			n _D ²⁰	Per Cent Toluene	cc.	n _D ²⁰	Per Cent Toluene	cc.
1st Extraction	800	140	1.4228	33.5	59	1.4168	27.5	—
2nd Extraction	300	59	1.4259	36.5	24	1.4199	30.5	—
3rd Extraction	125	24	1.4290	39.5	10	—	—	—

It will be seen from Table V that by a three-stage extraction it was possible to produce a fraction containing 39.5% of toluene.

A portion of the same toluene-heptane blend was extracted with the Solution A, the composition of which is given in Table I. 110 cc. of hydrocarbon mixture was mixed with 270 cc. of Solution A in the first-stage extraction. In the second-stage extraction 35 cc. of hydrocarbon, obtained from the extract layer, was again extracted with Solution A and 19 cc. of hydrocarbons was recovered from the extract layer and in the third-stage extraction, the 19 cc. of hydrocarbons from the extract layer was recovered having a toluene content of 40.5%. Table VI gives the data for the extraction showing the refractive index, toluene content and quantity of hydrocarbon extract from each step of the process.

Table VI

	cc. Solution A Used	cc. of Hydrocarbon Treated	Hydrocarbons Recovered from Extract Layer			Hydrocarbons Remaining in Upper or Raffinate Layer		
			n_{D}^{20}	Per Cent Toluene	cc.	n_{D}^{20}	Per Cent Toluene	cc.
1st Extraction	270	110	1.4234	34.0	35			
2nd Extraction	200	30	1.4273	38.0	19			
3rd Extraction	125	19	1.4300	40.5	14			

It will be seen, therefore, that by employing aqueous alkali solutions containing naphthenic acids or oxidation petroleum hydrocarbons in solution, fractions respectively richer in open-chain and closed-ring hydrocarbons can be prepared from a mixture of open-chain and closed-ring hydrocarbons.

Extraction solutions for use in our process should contain a substantial amount of free alkali metal hydroxide, and preferably at least 10% by weight should be present. The solution should also contain a substantial amount of naphthenic acid or oxidized petroleum soaps, preferably not less than 10% by weight and generally in excess of 15% by weight. The naphthenic acids or oxidized petroleum products may be added to the solution in the acidic form or in the form of the alkali metal soap thereof. Sufficient solventizers should be present to keep the naphthenic acid soaps in solution, but a substantial excess of solventizer over that necessary for maintaining a homogeneous solution is not desirable.

Solubility of the various hydrocarbons in the extraction solution will vary somewhat with the relative amounts of free alkali metal hydroxide, solventizer, and naphthenic acids or petroleum oxidation products present in the solution. In general, higher concentrations of free metal hydroxide and naphthenic acids or petroleum oxidation products produce solutions having greater solubility for hydrocarbons than do solutions containing lower concentrations. Care should be exercised not to use solutions which are so concentrated as to be too viscous and cause emulsion difficulties. Solutions containing up to 25% by weight of free alkali metal hydroxide and up to the maximum amount of soap soluble in the solution under extraction conditions work satisfactorily.

Care should be exercised not to increase the concentration of alkali metal hydroxide and/or naphthenic acids or petroleum oxidation products to the point where the solution is no longer homo-

geneous. We have found that the solutions of the composition given in Table I will remain homogeneous over the usual atmospheric temperature range.

Extraction may be effected over the range of atmospheric temperatures. Temperatures ranging from 32 to 126° F. have been used satisfactorily. The pressure maintained need only be sufficient to keep the hydrocarbons from vaporizing.

It is claimed:

1. The method of separating a mixture of open-chain and closed-ring hydrocarbons into a plurality of fractions at least one of which contains a higher proportion of open-chain hydrocarbons and at least one of which contains a higher proportion of closed-ring hydrocarbons than the original mixture comprising contacting said mixture with at least about 2 volumes of an aqueous

solution containing not less than about 10% by weight of free alkali metal hydroxide and not less than about 10% by weight of a substance selected from the group consisting of alkali metal soaps of naphthenic acids and petroleum partial oxidation products, separating the resulting mixture into two layers and recovering hydrocarbons from the extract layer.

2. The method of separating a mixture of aromatic hydrocarbons and open-chain hydrocarbons into at least two fractions one of which is richer in aromatic hydrocarbons and the other of which is poorer in aromatic hydrocarbons than the original mixture comprising contacting said mixture with at least about 2 volumes of an aqueous alkali solution containing not less than about 10% by weight of free alkali metal hydroxide and not less than about 10% by weight of a substance selected from the group consisting of soaps of naphthenic acids and of petroleum partial oxidation products, separating the resulting mixture into an extract layer and a raffinate layer and recovering hydrocarbons from the extract layer.

3. Method in accordance with claim 2 in which the free alkali metal hydroxide content of the solution is in excess of 10% by weight and the content of said substance is in excess of approximately 15% by weight.

4. Method in accordance with claim 1 in which the substance comprises naphthenic acid soaps and the solution contains sufficient solventizer to keep the soaps in solution.

5. Method in accordance with claim 1 in which the substance comprises naphthenic acid soaps and the solution contains sufficient cresols to keep the soaps in solution.

6. Method in accordance with claim 2 in which the substance comprises naphthenic acid soaps and the solution contains sufficient solventizer to keep the soaps in solution.

7. Method in accordance with claim 2 in which the substance comprises naphthenic acid soaps

and the solution contains sufficient cresols to keep the soaps in solution.

8. The method of separating a mixture of hydrocarbons containing cyclohexene into at least two fractions one of which is richer in cyclohexene and the other of which is poorer in cyclohexene than the original mixture comprising contacting said mixture with at least about 2 volumes of an aqueous solution containing not less than about 10% by weight of free alkali metal hydroxide and not less than about 10% by weight of a substance selected from the group consisting of soaps of naphthenic acids and soaps of partial oxidation petroleum products, separating the resulting mixture into an extract layer and a raffinate layer and recovering hydrocarbons from the extract layer.

9. Method in accordance with claim 8 in which the substance comprises naphthenic acid soaps and the solution contains cresols in sufficient amount to keep the soaps in solution.

10. The method of separating a mixture of open-chain and closed-ring hydrocarbons into at least two fractions one of which is richer in closed-ring hydrocarbons and the other of which is poorer in closed-ring hydrocarbons than the original mixture comprising contacting said mixture at atmospheric temperature with at least about 2 volumes of an aqueous solution containing not less than 10% by weight of free alkali metal hydroxide, not less than 15% by weight of alkali metal-naphthenic acid soaps and a sufficient amount of solutizer to keep the soaps in solution, separating the resulting mixture into an extract layer and a raffinate layer, and recovering hydrocarbons from the extract layer.

11. Method in accordance with claim 10 in which the solutizer is cresol.

12. The method of separating a mixture of open-chain and closed-ring hydrocarbons into at least two fractions one of which is richer in closed-ring hydrocarbons and the other of which is poorer in closed-ring hydrocarbons comprising contacting said mixture at atmospheric temperature with at least about 2 volumes of an aqueous solution containing not less than about 10% by weight of free alkali metal hydroxide and not less than 10% by weight of alkali metal soaps

of petroleum partial oxidation products, separating the resulting mixture into an extract and a raffinate layer, and recovering hydrocarbons from the raffinate layer.

5 13. Method in accordance with claim 12 in which the soaps of petroleum partial oxidation products are soaps of a product prepared by catalytic air oxidation of 36 to 40 Baumé gravity Pennsylvania petroleum distillate, which product

10 has the following properties:

Bé. gravity at 158° F.	11-9°
Specific gravity at 158° F.	1.007-0.9950
Viscosity (Saybolt) at 210° F.	91-101
Cold test (A. S. T. M.)	20-25° F.
15 Flash (C. O. C.)	250-270° F.
Fire (C. O. C.)	280-300° F.
Acid number	110-130
Saponification number	190-210
Iodine number	20 maximum
20 Ash	0.5-1.0

14. Method in accordance with claim 1 in which the aqueous solution is composed of:

	Per cent by weight
25 Sodium hydroxide	18
Naphthenic acids	18.7
Cresols	6.3
Water	56.7
